Fig. 5

Fig.6

Fig.7

Fig.8

FIGURE 1 is an elevational view of a hose fitting, showing my new design;

FIGURE 2 is an end elevational view thereof as seen from the right of FIGURE 1;

FIGURE 3 is an elevational view of a modified form of the hose fitting shown in FIGURE 1;

FIGURE 4 is an end elevational view thereof as shown in FIGURE 3;

FIGURE 5 is an elevational view of the female fitting shown in FIGURE 1;

FIGURE 6 is an end elevational view thereof as seen from the left of FIGURE 5;

FIGURE 7 is an elevational view of the female fitting shown in FIGURE 3; and

FIGURE 8 is an end elevational view thereof as seen from the left of FIGURE 7.

I claim:

The ornamental design for a hose fitting, as shown and described.
